THERAPEUTIC SULFONAMIDE
COMPOSITIONS

David Lehr, New York, N. Y.

No Drawing. Application August 18, 1945,
Serial No. 611,445

3 Claims. (Cl. 167—51.5)

1

This invention relates to novel compositions having new and valuable therapeutic properties.

A principal object of the invention is to provide sulfonamide drugs of lower toxicity, more complete utilization and increased effectiveness, by combining two or more of these compounds.

A particular object of the invention is the provision of sulfonamide drug compositions which will eliminate or substantially decrease the kidney damage attending the therapeutic use of the sulfonamide compounds heretofore available.

In the administration of sulfonamide drugs, it is the endeavor of the physician to produce and maintain a therapeutically effective concentration of the drug in the blood and other body fluids and tissues of the patient. However, a limit is placed on the concentrations of the drug which may be maintained in the body because of certain toxic reactions which increase in frequency and severity with increasing sulfonamide blood concentrations in the body, although there may be considerable variations with regard to the particular sulfonamide employed and also with regard to the individual patient treated. These untoward reactions constitute a significant drawback in the therapeutic employment of sulfonamides.

One of the most frequent and most serious of the toxic reactions encountered in the administration of sulfonamide drugs is renal obstruction. This has been shown to be due to the deposition of sulfonamide crystals and the formation of solid sulfonamide concrements in the urinary tract, which adversely affects the kidney functions both by mechanical obstruction and by damaging the kidney parenchyma.

I have found that renal toxicity due to the formation of renal concrements can be greatly reduced or eliminated without decreasing the therapeutically desirable concentrations of the drugs, or even with an actual increase in drug concentrations, and that all desirable therapeutic effects may be obtained to the same degree or even to an increased degree by means of mixtures of two or more sulfonamide drugs of different molecular constitution.

I have found that various sulfanilamide derivatives when mixed in the same solvent (water, urine) do not influence each other with regard to their individual solubilities. In other words, the

2

solubility of each component is about the same as if it were the only compound present in the solvent. The sulfonamide concentration of a saturated sulfonamide mixture corresponds therefore, to the sum of the solubilities of all its components. This is true whether the drugs are closely related in structure or are of substantially different structural composition. This substantially additive solubility is found to exist with mixtures of homologous sulfonamide drugs, such as sulfadiazine (2-sulfanilamidopyrimidine) and sulfamerazine (2-sulfanilamido-4-methylpyrimidine), with mixtures of isomeric sulfonamide drugs, such as sulfadiazine and sulfapyrazine (2-sulfanilamidopyrazine), and with mixtures of sulfonamide drugs of relatively unrelated chemical structure, such as, sulfadiazine and sulfathiazole (2-sulfanilamidothiazole).

By means of the mixtures of sulfonamide drugs of the invention, it is possible to maintain highly effective concentrations of the drugs in the body fluids while preventing the concentration of any single drug in the mixture from closely approaching levels at which, in accordance with general clinical experience, renal toxic effects are known to appear. The sulfonamide drugs in the mixture may be selected and proportioned as to produce the best therapeutic effect or combination of effects in accordance with the particular localization of the infection (lungs, meninges, urinary tract, etc.) and also in accordance with the type of the invading organism. If desired, either to obtain a special therapeutic effect, or to still further reduce the concentration of one or more of the drugs in the composition, mixtures of three or more sulfonamide drugs may be provided, for example, sulfathiazole, sulfadiazine, sulfamerazine and sulfamethazine (2-sulfanilamido-4,6-dimethylpyrimidine).

The component sulfonamide drugs of the compositions of the invention may include N^1 -heterocyclic compounds such as those specifically mentioned above, non-cyclic N^1 -substitution products such as sulfaguanidine, and N^4 -substitution products such as succinylsulfathiazole, and, in general, compounds of the general formula

wherein M represents hydrogen or a cation, R represents a heteroatomic chain or a heteroatomic ring, and A represents hydrogen or an acyl radical.

In general, the most effective results in reduction of renal toxicity are obtained when the individual sulfonamide components of the mixture are present in approximately equal proportions, although the beneficial effects of the invention may be obtained when the proportions of the sulfonamide components vary over the range of 1:1 to 1:3 molar equivalents and the term "substantially equal" as used herein is intended to express this range of proportions.

The remarkable reduction in toxicity provided by the compositions of the invention is strikingly illustrated by the following series of acute and chronic toxicity tests on albino rats using the sodium salts of sulfadiazine (NaSD) and sulfathiazole (NaST) and mixtures of the two:

ACUTE TOXICITY

Drug, gm. per Kg. body weight	No. of Animals	Per Cent Death	Remarks
Single intra-peritoneal injection of—	Sulfonamide total amount		
NaSD, 1.5—	1.5	10	90 Died within 1 to 3 days.
NaST, 1.1—	1.1	15	67 Died within 1 to 4 days.
NaSD, 0.75—	0.75	10	0 Mixture of one half of each of the above dosages. Complete recovery.
NaST, 0.55—	0.55		
	1.3		

CHRONIC TOXICITY

Drug, gm. per Kg. body weight	No. of Animals	Per Cent Death	Remarks
Daily intra-peritoneal injection of—	Sulfonamide total amount		
NaSD, 0.9—	0.9	10	100 Died within 3 to 6 days.
NaST, 0.9—	0.9	10	100 Died within 1 to 4 days.
NaSD, 0.45—	0.45	10	40 Died within 3 to 7 days.
NaST, 0.45—	0.45		
	0.9		

The animals were injected for a maximum of 6 consecutive days.

Evidence derived from chemical analyses of blood and urine indicated a significant decrease of renal obstruction, following administration of the mixed sulfonamides, as the chief reason for the strikingly low toxicity of the mixture. This could be inferred in particular from a comparison of the non-protein nitrogen levels in the blood and from comparative follow-up studies of the sulfonamide concentration in blood and urine at predetermined intervals. When a dosage representing the same total sulfonamide content was used, the sulfonamide blood levels obtained with the mixture were much higher than from sulfathiazole alone, and only slightly lower than from sulfadiazine alone. The average total sulfonamide values (mean of 10 animals) for the dosages used in the acute toxicity study were, after 24 hours, for sulfadiazine: 121 mg. per cent, for sulfathiazole: 45 mg. per cent, and for sulfadiazine-sulfathiazole: 85 mg. per cent. After the same interval, the urinary drug excretion per rat (means of 10 animals) had reached 29 mg. for sulfadiazine, 34 mg. for sulfathiazole, and 72 mg. for sulfadiazine-sulfathiazole. The strikingly high renal excretion of the mixture from blood levels distinctly lower than in the sulfadiazine

group, indicated a diminution or even absence of renal obstruction in the animals receiving the sulfonamide combination. Further support for this viewpoint was derived from the marked difference in the non-protein nitrogen values of the surviving rats 48 hours after the drug injection (mean values: sulfadiazine group 182 mg. per cent, sulfathiazole group 120 mg. per cent, sulfadiazine-sulfathiazole group 82 mg. per cent), and also from post mortem examinations, especially of the urinary tract, which showed little or no renal damage in the animals treated with the mixture as compared to very definite renal damage when either of the sulfonamides was given separately in the same total dosage.

The experimental observations on laboratory animals were substantiated by clinical trials with the sulfadiazine-sulfathiazole combination which demonstrated a striking reduction in the incidence of crystalluria and complete absence of renal toxic effects despite the intentional omission of adjuvant alkali therapy.

Some of the sulfonamide compositions of the invention show, in addition to the decreased renal toxicity, a definite improvement in the therapeutic effect. In other words, sulfonamide mixtures may show a better curative effect than any one of the component drugs. This viewpoint was derived from clinical observations. It was confirmed by in vitro antibacterial studies which disclosed that, for example, mixtures of equal parts of sulfathiazole and sulfadiazine or of sulfadiazine and sulfamerazine, were, in many instances, significantly more effective against strep. hemolyticus, staph. aureus, pneumococcus and E. coli than any of the three drugs used alone in the same total concentration.

The compositions of the invention may be dispensed in powder form, compressed into tablets, in solution (particularly in the form of the sodium salts) or in any other desirable form, and any desirable and compatible substances may be added thereto to aid or improve the compounding, dispensing or administration of the compositions. The compositions defined in the claims hereof are intended to include the salts of the defined components.

I claim:

1. A therapeutic composition prepared for the internal administration of sulfonamide drugs consisting of a mixture of substantially equal amounts of at least two p-aminobenzenesulfonamide compounds differently substituted at the N¹-nitrogen by a radical selected from the group consisting of heteroatomic chains and heteroatomic rings, the amount of each component in each dose being substantially less than the full dosage of such component of the mixture that would be given if such component were given alone, whereby the renal toxicity is substantially reduced without reduction of the therapeutic effect as compared with the toxicity and therapeutic effect of each of said mixture components when given singly in full dosage.

2. A therapeutic composition prepared for the internal administration of sulfonamide drugs consisting of a mixture of substantially equal amounts of 2-sulfanilamidothiazole and 2-sulfanilamidopyrimidine, the amount of each component in each dose being substantially less than the full dosage of such component of the mixture that would be given if such component were given alone, whereby the renal toxicity is substantially reduced without reduction of the therapeutic effect as compared with the toxicity and

therapeutic effect of each of said mixture components when given singly in full dosage.

3. A therapeutic composition prepared for the internal administration of sulfonamide drugs consisting of a mixture of substantially equal amounts of 2-sulfanilamidothiazole and 2-sulfanilamido-4-methylpyrimidine, the amount of each component in each dose being substantially less than the full dosage of such component of the mixture that would be given if such component were given alone, whereby the renal toxicity is substantially reduced without reduction of the therapeutic effect as compared with the toxicity and therapeutic effect of each of said mixture components when given singly in full dosage.
